DESIGN FOR A TIP-OVER SWITCH CASE OR THE LIKE

Paul S. Bear and Herbert E. Bucklen, Elkhart, Ind., assignors, by mesne assignments, to Bucklen-Bear Laboratories, Inc., Elkhart, Ind., a corporation of Indiana

Application November 10, 1937, Serial No. 72,763

Term of patent 7 years

To all whom it may concern:

Be it known that we, Paul S. Bear and Herbert E. Bucklen, citizens of the United States, residing in Elkhart, in the county of Elkhart and State of Indiana, have invented a certain new, original, and ornamental Design for a Tip-Over Switch Case or the like, of which the following is a specification, reference being had to the accompanying drawing, forming a part thereof.

In the drawing:

Figure 1 is a side elevational view of a tip-over switch case showing our new design. The opposite side of the case is substantially identical in ornamentation and configuration with the omission of the two screws within the semi-circular recesses.

Figure 2 is a bottom plan view of the switch case shown in Figure 1; and

Figure 3 is an end elevational view taken along the line of the arrow 3 of Figure 1.

The dominant features of our design reside in a switch case of the particular configuration shown, and having the faces thereof ornamented as best illustrated in Figure 1.

We claim:

The ornamental design for a tip-over switch case or the like, as shown and described.
